ADVERTISING MECHANISM

Andrew J. Chesson, Lake Lure, N. C.

Application April 3, 1934, Serial No. 718,813

7 Claims. (Cl. 40—37)

This invention relates to an advertising mechanism and more especially to an endless sign driven by any suitable power such as a windmill, together with a peculiar arrangement of parts for the accomplishment of desired results in advertising.

It is an object of this invention to provide an advertising mechanism having a bill board for the reception of "still" advertising matter and said bill board having windows therein through which displays can be read from a plurality of moving signs appearing through said windows, said moving displays being so arranged that some of the display will be visible through one window and the remainder of the display will be visible through the other window.

It is another object of this invention to provide an advertising mechanism having a movable endless belt which has secured thereon a plurality of vanes for the reception of display matter and so arranged that several of the vanes can be seen at the same time, and if desired an arrangement can be provided whereby a portion of each vane can be rendered visible from one portion of the mechanism while the other portion of the vane is hidden from view with the purpose of exhibiting the other portion of the vane at another point in the mechanism.

It is a further object of this invention to provide a movable sign driven by a windmill provided with means for regulating the speed of the windmill so that the speed of the movable sign will not exceed certain limits whereby the sign will always be readable and will not be rendered obscure by too great a speed being imparted thereto.

Some of the objects of the invention having been stated, other objects will appear as the description proceeds when taken in connection with the accompanying drawings, in which:—

Figure 1 is an elevation of my advertising mechanism;

Figure 2 is an elevation of the lower portion of Figure 1, with the display board removed;

Figure 3 is a vertical sectional view taken along the line 3—3 in Figure 1;

Figure 4 is an enlarged vertical sectional view of the upper central portion of Figure 3;

Figure 5 is a view similar to Figure 4 but showing a modified form of the rollers and trackways;

Figure 6 is a view taken along line 6—6 in Figure 2;

Figure 7 is a front elevation of a portion of the windmill;

Figure 8 is a cross-sectional view taken along the line 8—8 in Figure 7;

Figure 9 is a cross-sectional view taken along the line 9—9 in Figure 7.

Referring more specifically to the drawings, the numerals 10 and 11 indicate suitable posts of a tower, there usually being two other posts immediately behind the posts 10 and 11 forming the tower which has on the upper end thereof a bearing plate 12 on which is rotatably mounted the member 13 having suitable bearing connections with plate 12 so that member 13 can rotate with respect to bearing plate 12. Member 13 has a pair of rudders 14 and 15 which serve the double purpose of acting as a rudder for the windmill and also for the reception of advertising matter. On the other end of member 13 there is disposed a pair of bearings 16 and 17 in which is rotatably mounted a shaft 18, said shaft having on the outer end thereof a hub 19 of a windmill. The other end of shaft 18 has a beveled gear 20 thereon meshing with the beveled gear 21 mounted on the upper end of a shaft 22 which has a suitable universal joint 23 therein connected to a drive shaft 24. The lower end of drive shaft 24 has a beveled gear 25 thereon meshing with another beveled gear 26 fixed on a shaft 27 which is mounted in suitable bearings in the framework of the tower. Shaft 27 has a pulley 28 thereon adapted to receive a belt 29 for driving an endless sign disposed in the lower portion of the apparatus and which will be presently described.

A suitable idler pulley 29a is provided for pressing against belt 29 to keep the same taut at all times.

The windmill proper comprises a plurality of radially disposed spokes 30 secured in hub 19 and having suitable brackets 31 and 32 fixedly mounted thereon, confining for rotative movement, brackets 33 and 34, which brackets are secured to a blade 35 of the windmill. The hub 19 has fixedly secured therein pins 36 for limiting the windward movement of the blades 35. Each spoke 30 has secured thereto a tension spring 38 and the other end of the tension spring is secured to the adjacent blade 35 of the windmill. In addition to spring 38 for allowing the blades 35 to feather and to decrease the angle of attack according to the velocity of the wind, there is also provided a mechanism shown in Figure 8, for assisting in this purpose. Each of the spokes 30 has fixedly secured thereon brackets 31 and 32 which in turn are connected to blade 40 which has mounted thereon a tube 41 threaded on its exterior for receiving a threaded cap 42 which has a hole therein adapted to be slidably penetrated by an arcuate bolt 43 receiving a nut 44. Dis-

posed inside tube 41 and surrounding arcuate bolt 43 is a compression spring 45. The other end of bolt 43 is fixedly secured to the rear side of the blade 35 of the windmill. This arrangement allows the blade 35 to feather and to adjust its angle of attack according to the velocity of the wind and also the fixed blade 40 serves as a buffer to prevent pressure from being built up on the back side of the blades 35 of the windmill. It is well known that with wind blowing against the front surface of the blades that almost equal pressure is built up on the rear surface of the blades and by providing the fixed blades 40 set at an angle to decrease their braking power, it prevents the wind from passing around the leading edges of the blades and building up a pressure on the back side of the blades. This increases the efficiency of the windmill and causes it to start more easily and to operate in a wind of much less velocity than were the fixed blades 40 not present.

Vertically disposed on the tower or supported by any suitable means such as posts 54 and 54a is a board 50 and disposed in front of board 50 and spaced therefrom is a display board 51 having windows 52 and 53 therein. Secured on the posts 54 and 54a are the bearing brackets 55 in which are mounted shafts 56 and 57 having mounted thereon pulleys 58 and 59, the pulley 58 being driven by belt 29. The shaft 56 has fixed thereon and disposed immediately behind pulley 58, a pulley 46, on which belt 29 is mounted. Pulleys 57 and 58 have mounted thereon an endless belt 60 which belt has secured thereon, by any suitable means such as rivets 61, a plurality of vanes 62, 63, 64, 65, 66, 67, 68, 69, 70 and 71. These vanes have a pin 72 projecting therethrough on which rollers 73 and 74 are mounted which are adapted to fit into grooved endless trackways 75 and 76 disposed on the proximate faces of boards 50 and 51. These guide the vanes and prevent their sagging downwardly in the central portion of the endless belt in case it should become slack.

It is to be noted that vanes 62 to 71 inclusive, have duplicate advertising disposed thereon, one above the other and one in an inverted position with relation to the other, and the windows 52 and 53 are so arranged that the tip ends of the vanes are visible through window 52 whereas the butt ends of the vanes are visible through the window 53. In other words, the parts of the vanes farthest removed from the belt 60 are visible through window 52 whereas the parts of the vanes which are nearest the belt 60 are visible through the window 53. This gives a double advertisement for each advertiser visible through the upper and lower windows.

It is also to be noted that by connecting the vanes to the belt at a single point by rivets 61, that a pivotal connection is obtained as will be shown with relation to vanes 66 and 71 as they pass around the pulleys 57 and 58.

In Figure 5 a slightly modified form of the invention is shown in which, instead of having pin 72 with the rollers thereon, each side of the vane has a suitable bracket 80 thereon on which is mounted a flanged roller 81 which is adapted to follow a plain trackway 82 fixed on the proximate surfaces of boards 50 and 51.

It is also to be noted that pulley 28 is in the form of an automobile tire and the advertisement on board 86 disposed immediately thereabove has an arrow 87 pointing to the revolving wheel imitating an automobile tire so as to in-

crease the effectiveness of the advertisement on board 86, this being peculiarly adaptable for a tire advertisement.

It is to be noted that the printed matter appearing on vanes 62 to 71 is merely illustrative and where the word "Radio" appears, of course the complete advertisement of some radio store would appear, or if desired, the sign can be used entirely by one firm which could have the fixed advertisement of the firm on the board 51 and the various articles handled by the firm could be displayed on the revolving belt. This would give a complete line of correlated advertising for a single firm if desired. Also window 52 could display the advertisements of one firm and window 53 could be devoted to the advertisements of another firm.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. An advertising mechanism having a pair of boards disposed one in front of the other and spaced from each other, the proximate faces of each board having a trackway secured thereon, an endless belt disposed between the boards, a plurality of vanes secured at one end of the belt and having rollers intermediate their ends adapted to follow said trackways, said vanes being adapted to have advertising matter thereon, said front board having a window therein through which the signs on said vanes are visible as they move with the endless belt.

2. An advertising mechanism comprising a tower, a wind-mill mounted on said tower, a vertically disposed board mounted on the lower portion of said tower, a second vertically disposed board mounted in front of the first board and spaced therefrom, a pair of pulleys mounted for rotation between the boards, an endless belt mounted on said pulleys, means connecting the windmill to one of the pulleys for driving the endless belt, a plurality of vanes secured on said endless belt and adapted to have advertising matter placed thereon, said front board having at least one window therein through which at least a portion of the advertising matter on said vanes is visible.

3. An advertising apparatus comprising a tower, a vertically disposed board mounted on the lower portion of said tower, a second vertically disposed board mounted in front of the first board and in spaced relation thereto, a pair of pulleys mounted for rotation between the boards, an endless belt mounted on said pulleys, a windmill mounted on top of the tower and having driving connections with one of said pulleys, a plurality of vanes having one end secured to said belt and adapted to have advertising matter thereon, the proximate surfaces of each board having a track thereon, means on said vanes engaging said tracks for guiding said vanes, said front board having a window therein through which at least a portion of the advertising matter on the vanes is visible.

4. An advertising apparatus comprising a tower, a vertically disposed board mounted on the lower portion of said tower, a second vertically disposed board mounted in front of the first board and in spaced relation thereto, a pair of pulleys mounted for rotation between the

boards, an endless belt mounted on said pulleys, a windmill mounted on top of the tower and having driving connections with one of said pulleys, a plurality of vanes having one end secured to 5 said belt and adapted to have advertising matter thereon, the proximate surfaces of each board having a track thereon, means on said vanes engaging said tracks for guiding said vanes, said front board having a pair of windows there- 10 in, a portion of each vane being visible through one window and another portion of the vanes being visible through the other window.

5. An advertising apparatus comprising a tower, a vertically disposed board mounted on 15 the lower portion of said tower, a second vertically disposed board mounted in front of the first board and in spaced relation thereto, a pair of pulleys mounted for rotation between the boards, an endless belt mounted on said pulleys, 20 a windmill mounted on top of the tower and having driving connections with one of said pulleys, a plurality of vanes having one end secured to said belt and adapted to have advertising matter thereon, the proximate surfaces of each board

having a track thereon, means on said vanes engaging said tracks for guiding said vanes, the vanes having two advertisements thereon, one advertisement being inverted with relation to the other, and said front board having two windows therein, one portion of each vane being visible through one window and the other portion of the vanes being visible through the other window.

6. A windmill having pivoted blades, a fixed 10 blade associated with each blade and disposed rearwardly thereof and resilient means disposed between the pivoted blades and the fixed blades to allow the velocity of the wind to adjust the angularity of the blades. 15

7. A windmill having a plurality of radially disposed spokes, a blade pivotally mounted on each spoke, a fixed blade on each spoke and disposed rearwardly of the pivoted blade and a resilient device disposed between the fixed and 20 pivoted blades to permit the velocity of wind to automatically adjust the angularity of the pivoted blades.

ANDREW J. CHESSON.
